[57] **CLAIM**

The ornamental design for a shift control lever unit, as shown and described.

DESCRIPTION

FIG. 1 is a side elevational view of a shift control lever unit showing my new design;

FIG. 2 is a top plan view thereof looking in the direction of arrows 2—2 in FIG. 1;

FIG. 3 is a front elevational view thereof looking in the direction of arrows 3—3 in FIG. 1; and

FIG. 4 is a side and rear perspective view thereof.
